UNITED STATES PATENT OFFICE

2,562,811

REFRIGERATOR

Glenn Muffy, Springfield, Ohio

Application September 15, 1945, Serial No. 616,523

19 Claims. (Cl. 62—103)

1

This invention relates to refrigerators, particularly to those of the domestic type, and has for its principal object the provision of a device of this type having certain new and useful features rendering it of greater usefulness than conventional constructions.

One purpose of this invention is to provide dehydrating means for a dry storage space for foods not necessarily refrigerated.

Another object is to provide a small compartment within the refrigerated space which is held at a slightly higher temperature, particularly for the short-time storage of butter.

A further object is to utilize the heat transfer which warms the butter compartment for the additional purpose of dehydrating air in the warm dry storage compartment.

A still further object is to provide for draining moisture condensed within the main food compartment into the condensing unit compartment along with the moisture collected by dehydration of the warm dry compartment, discharging all such water onto a warm portion of the condensing unit so as to re-evaporate it to ambient air.

In the drawings:

Fig. 1 is a sectional view of the lower part of a household refrigerator showing the warm, dry compartment.

Fig. 2 is a fractional view of Fig. 1, showing a modified form of the dehydrating device.

Fig. 3 is a view similar to Fig. 2, showing a further modification in which the dehydration is accomplished by means of the suction tube instead of by the cooling effect of the refrigerator liner.

Fig. 4 is a third modification, quite similar to Fig. 3, but arranged for location of the dehydrating coil in the machinery compartment instead of in the storage space.

Fig. 5 is a further modification in which the butter compartment 76 is warmed by heat transferred from the dehydrating coil 78 to the liner of the main food compartment by means of a secondary refrigerant circuit.

Fig. 6 is another modification in which provision is made for collection of condensate from the main food space of the cabinet, this water being evaporated to room air by the same means employed for evaporating the water removed from air in the warm, dry storage compartment.

Fig. 7 is a modified detail of Fig. 6 showing solid cone 84 in place of the sheet metal cone 82.

Fig. 8 is an alternative arrangement for dehydrating compartment 1 and dissipating moisture to the compartment 11 by means of an absorbent or adsorbent.

2

In the drawings, the refrigerator cabinet is identified by the numeral 1 and the liner by the numeral 3. The bottom sheet, below the insulation, is identified by the numeral 5 throughout the figures, and will serve in connection with the insulated dividing wall 8 between the dry storage compartment 7 and the machinery compartment 11 to show the relationships of the figures. The compartment 1 represents an improvement over the compartment enclosed by housing 18d, Fig. 1 of my United States Patent No. 2,145,773, issued January 1, 1939, and described on page 3, column 1, lines 58 to 68 thereof. In addition to being heated through the wall which divides it from the condensing unit compartment, as in the issued patent, the present application discloses means for dehydrating the air of the warm, dry compartment 1.

The motor-compressor assembly 13 is located in the compartment 11 and the drawer 18 in the compartment 1. The floor 17 of the compartment 7 may or may not extend to form a floor for the compartment 11, but in any event it is desirable to have the compartment 7 closed by this floor and by the drawer front 18. A gasket 21 is provided to minimize air leakage between the drawer front and the cabinet face. A drawer pull may be made by cutting through the face of the drawer front, but is preferably made air tight by means of a stamped metal drawer pull closure 23, with which the drawer catch 24 may be integrally formed. This drawer catch engages the spring 25, which is attached to a fixed portion of the cabinet. This spring and catch are so related that the drawer front is held against the gasket when the drawer is closed.

The dehydrating tube 21 of Fig. 1 has attached to it, preferably by welding, one or more angles 29, the horizontal legs of which contact the liner 3. Air flows from the compartment 7 by way of the fitting 31 and the tube 33 into the dehydrating tube or chamber 27, where the air is chilled sufficiently to condense some water from it and the dehydrated air returns through the tube 35 to the compartment 1. Water collecting in the tube 27 flows to the right and collects in the trap 37 until there is sufficient water to drain through the tube 39, whereupon the condensate falls upon the motor-compressor unit 13 and is evaporated to ambient air by the heat of this unit. Where the tube 39 passes through the sheet 5, a sealing and vibration absorbing flange member 41, made of rubber or equivalent material, is arranged to prevent flow of air into the insulation in the refrigerator wall from the exterior. Likewise, the tubes 33 and 35 are sealed to the sheet 5 by

means of somewhat similar grommets or sealing devices 42. If desired, these tubes may be welded to the sheet 5, but in the case of Fig. 1, a vibration absorbing connection is shown for reasons which will be apparent from later description herein.

The discharge tube 45, which leads from the compressor to the condenser, has a heat exchange section 41 in thermal contact with a portion of the tube 33 within the space 11. Hot gas leaving the compressor is thus made to heat the column of air within the vertical tube 33, thereby inducing an upward flow of air in the tube 33 and a downward flow of cooler air through the tube 35. Flow of air through the tube 35 is prevented by the water collected in the trap 37. It will be observed that the tube 33 extends upwardly into the tube 27 far enough to prevent condensate from draining into the tube 33, and that the upper end of the tube 33 is above the water level in the trap 37.

The angle 29 welded to the tube 27 may merely contact the liner 3 or be welded thereto. The former is suggested as preferable for ease of assembly.

In order to obtain a greater heat transfer from the dehydrating device to the cabinet liner, a stamping 51, as shown in Fig. 2, may be substituted for the pipe 27. The pipe 33 serves the same purpose as in Fig. 1 and pipes 135 and 139 are equivalent to 35 and 39, respectively. The trap effect is obtained in the bottom of the stamped pan 51 by means of the return bend at the top of pipe 139. Variations in the area covered by the pan 51 on the bottom of the liner 3, or in the conductivity provided between the pipe 27 and the liner 3, will make it possible for the designer to provide ample cooling effect for the dehydration of air without allowing excessive heat transfer which will seriously affect the efficiency of the refrigerator as a whole.

Fig. 3 shows the suction tube 60 formed into a coil 61 within the dry storage compartment 1. This coil is relatively cool, so that, in the event of there being high humidity air in the compartment 1, condensate will collect on this coil and drip into the pan 63. Such condensate will flow through the trap 237 in the tube 238 to drip onto the motor-compressor unit 13 as explained in connection with Fig. 1.

The construction of Fig. 3 avoids the necessity for passing tubes through the bottom sheet 5, but occupies some space in the compartment 1, thereby calling for a reduction in the height of at least a portion of the side walls of the drawer 15.

The method of Fig. 3 may be modified as shown in Fig. 4 to avoid use of space in the compartment 1. The tube 60 is formed into a coil 161 located in the condensing unit chamber 65, which is enclosed by an insulated wall 67. The chamber 65 is connected with the compartment 1 near the top and bottom of 65, so that the warmer air in compartment 1 will flow into chamber 65 through the upper one of these passages and return through the lower one. Preferably, the direction of flow of suction gas through the coil 161 is upwardly, as indicated, but this is not necessary, particularly if the chamber 65 and the coil 161 are made more nearly flat and with less height. A trap 337 is formed in the tube 339 for the purpose described in connection with the other figures.

In Fig. 5, the insulated chamber 65 is enclosed by insulated wall 67 as in Fig. 4, but the cooling

effect is obtained from the small enclosure 76 by means of the coil 77 and the coil 78 instead of cooling the space 65 with a section of the suction tube as is done in Figs. 3 and 4. The coils 77 and 78 are formed of one continuous tube and charged with a volatile refrigerant so that they form a secondary refrigerating system of which 77 is the condenser and 78 is the evaporator.

Liquid refrigerant evaporates in the coil 78 and the vapor flows upwardly to the coil 77 where it recondenses and the liquid flows back to the bottom of coil 78 where it is again evaporated to absorb heat from the space 65 and from water vapor condensed upon the coil from air which circulates between the space 1 (Fig. 4) and space 65. The condensation of refrigerant vapor in the coil 77 heats the portion of the liner 3 immediately below the space 76. This space is enclosed and provided with a door so that the temperature of the space 76 may be several degrees higher than the air temperature prevailing within the main food compartment of the refrigerator. The main purpose of this small space 76 is for the storage of butter at a temperature suitable for table use. A fractional portion of the compartment 76 is also seen in Figs. 1 and 2. Such compartments have in the past been heated by electrical means or by heat leakage from outside of the refrigerator, but the arrangements shown by Figs. 1, 2, 5, 6 and 7 are improvements over previous practice in that the heat transfer device which warms the butter compartment serves the additional purpose of dehydrating the air of the warm dry compartment 1.

While a small amount of heat is allowed to enter the refrigerated space for the purpose of warming the butter compartment 76, this heat transfer accomplishes the additional purpose of dehydrating the air of compartment 1. This is more efficient than the previous practice of allowing heat from the room to enter the butter compartment directly. It is much more efficient than the practice of placing an electrical heating element within the butter compartment, which not only robs the refrigerator of some of its refrigeration, but uses electrical energy in doing so.

Fig. 6 shows the butter compartment 76 heated in a different manner without the use of the secondary refrigerating system 77-78. Heat is transferred to the butter compartment by metallic conductivity through the tubular member 82 which is contacted internally by air in open communication with the compartment 76 and externally by air in open communication with the compartment 1. The result is a slight warming of the compartment 76 and the condensation of moisture on the outer surface of the member 82.

The cup 84 is inturned at its top to minimize air circulation and splash of water while allowing water to drain into it from the outside of 82. Tube 86 may extend upward within 82 to form a trap to prevent air flow into and out of the refrigerated space if desired. When the water level rises sufficiently within the trap 84 or 88 it flows from the outlet 89 onto the motor-compressor unit 13.

Fig. 6 also illustrates the method of disposing of condensate which collects on the lining of the food compartment or on any cooling surface within that compartment. As shown in Fig. 6, the rear lining of the food compartment is cooled by an evaporator coil 90 so that the lining of

the food compartment also acts as the cooling surface for that compartment. Preferably, the temperature of the liner is not low enough to collect and hold frost, thus moisture which condenses on the liner is free to flow downwardly into the gutter 92 which extends across the rear of the bottom of the liner and forwardly on each side in case the side walls of the liner are also cooled. This gutter 92 may have a slight fall so that water drains into the gutter 94, which is located below the butter compartment and concealed thereby. The gutter 94 drains into the interior of the tubular member 82, so that all moisture collecting on the cooling surfaces of the main food compartment will drain into the trap in 88 to join the water collected on the outside of the tubular member 82 from the air of compartment 7.

The moisture thus collected may optionally drip at the outlet 88 onto the housing of the motor-compressor unit, as shown herein, onto the condenser connected therewith or onto a fibrous material or extended surface from which the water evaporates readily to room air. The flow of condensate will be substantially constant and at a very low rate, so that it is quite easily evaporated to the air of the room in which the refrigerator is located.

By extending the bottom end of 82 and dropping the cup 84 a corresponding distance the water level, which is barely visible in the cup 84 in Fig. 6, will seal the bottom end of the tubular member 82. The sealing at this point is optional since a slight leakage of air also serves the purpose of heating the compartment 16 and dehydrating the compartment 7, either by dilution of its atmosphere with cooler air which contains less water vapor per cubic foot or by the migration of water vapor from compartment 7 to the refrigerated space.

In Fig. 6 the unit 13 is shown as supported by means of four springs which connect the ears 96 with the supports 98. High pressure vapor from the compressor passes through tube 45 to the condenser 100 and liquid refrigerant flows from the condenser through capillary tube 102 to the evaporator 90, which contacts the liner 3 to cool the air in the main food compartment.

In Fig. 7 the lining 3 has a much smaller hole through it than is seen in Fig. 6, this hole registering with the center of the cone 104 so that water which drains down the gutter 94 enters the hole 105. Surrounding this solid metal cone which provides high conductivity there is a conical baffle 106 which may be made of metal or of thermally non-conductive material. This cone is provided with a number of openings 107 for the circulation of air and its bottom diameter is less than the top diameter of the cup 109 from which water drips from the cone 104 or the cone 106. These parts are located inside of a sleeve 111 which may be either metallic or of non-conducting material, the sleeve being gasketed to the liner 3 and to the bottom sheet 5, to each of which it is secured by means of screws. The upper screws may also secure the cone 106.

Air follows the path indicated by arrows, contacting the cold cone 104 and condensing moisture thereon to drip into the cup 109 and fill the trap 88 before draining through the outlet 88 which is seen in Fig. 6.

Fig. 8 illustrates a modification of the invention in which moisture from the space 1 is absorbed or adsorbed and later released in the warmer compartment 11 as the hygroscopic agent

carrying the water is activated by the rise of temperature occasioned by rotation of the cylinder or drum 114.

This drum is supported by its shaft 116 which has end bearings in the insulating wall 9 and is surrounded by thermal insulation 118, which forms the core of the cylinder 114. Immediately surrounding the insulating material is a sleeve 120 and radiating from this are dividing walls 122. Both 120 and 122 may optionally be made of metal or non-conducting material. The spaces between the dividing walls 122 are filled with an absorbent or adsorbent material 124 which may for instance be silica gel. Surrounding the extremities of the walls 122 and enclosing the material 124 is a screen 126 and outside of this a cylinder 128 of perforated metal.

In use the drum 114 is balanced and mounted on substantially frictionless bearings so that a slight increase in gravity of the material 124 which is exposed to the space 1 will cause that side of the drum 114 to fall, thus providing the energy for rotating the drum. When the absorbent material is exposed to the cooler compartment 7 it absorbs moisture and when it is exposed to the warmer compartment 11 it loses moisture by evaporation, thus the average density of the material 124 exposed to the space 1 will be greater than that of the partially dried material exposed to the warmer compartment 11. The effect is to transfer moisture from the air of space 1 to the air of space 11, which is open to the atmosphere of the room so that the moisture is dissipated.

Instead of the continual evaporation of a small amount of condensate, the material used to absorb or adsorb water might in the above case be periodically activated by means of heat. This period of activation might coincide with the cycling of the condensing unit, thus making the activation automatic during each running period of the compressor or other pressure imposing element. For the purpose of simplicity in this specification and claims, I herein use the word "absorb" in its broader sense, including both absorption and adsorption.

Referring again to Fig. 1, it will be noted that the motor-compressor unit 13 is supported by means of springs 70, which are attached to the tube 39. This method of supporting the motor-compressor unit is made practicable by the presence of the tube 39 and the fact that it is supported by the vibration absorbing member 41. To provide against excessive sway of the motor-compressor unit and to hold it in place during shipment, the stops 75 are attached to the base of the cabinet and so spaced as to allow a limited amount of free movement of the assembly 13. There are preferably three of the springs 70 and three of the stops 75, one of the latter being located as shown in Fig. 1 so that only this one stop need be removed for removal of the unit 13. By locating the upper end of the stops 75 nearer to the bottom edge of the unit 13, it will be possible to remove the unit 13 without removing any of the stops 75. The unit 13 is merely lifted so that it rests upon one or more of the stops 75 while the springs 70 are unhooked.

What I claim is:

1. In a refrigerator cabinet, means enclosing a relatively large refrigerated space, means enclosing a relatively small space in heat transfer relation with said large space, means enclosing a third space in said cabinet arranged to be maintained at a higher temperature than either of

the first two said spaces, and heat transfer means being so constructed and arranged as to cause condensation of moisture from the air in said higher temperature space and to convey a limited quantity of heat to said small space.

2. In a refrigerator, a main food storage compartment, means for refrigerating said compartment, a smaller compartment within said main compartment cooled by conduction of heat therefrom to said main compartment, a third relatively warm compartment outside of said main compartment, and heat transfer means arranged to dehydrate the air of said warm compartment by conducting heat from said air to said smaller compartment.

3. In a refrigerator, a thermally insulated compartment, cooling means exposed to air within said compartment, a smaller compartment in thermally conductive relationship with the first said compartment, a substantially non-refrigerated space located outside of the first said compartments, and heat exchange means arranged to transfer a limited amount of heat from said non-refrigerated compartment to said smaller compartment, such transfer of heat being effective to increase the temperature of said smaller compartment and to condense water vapor from air within said non-refrigerated compartment.

4. In a refrigerator, a cool food storage space, means for cooling air in said space and thereby condensing water from the air of said space, a warm dry compartment, means for condensing water from the air in said warm dry compartment and thereby decreasing its humidity, and means for re-evaporating water condensed by both said means to air exterior of said spaces.

5. In a refrigerator having insulated walls, a refrigerating system, a food storage space enclosed by said walls and cooled by said system, a liner for said space, means exterior of said space for cooling a vertical wall of said liner and thereby collecting moisture from the air in said space, a warm dry compartment accessible for the storage of foods, and means for condensing water from the air of said compartment and draining it into direct contact with a heat dissipating portion of said system for re-evaporating the water so that its vapor mixes with the air of the room in which the refrigerator is located.

6. In a refrigerator cabinet, a warm dry compartment, a relatively cool compartment, a refrigerating system arranged to cool said relatively cool compartment, and a sealed secondary refrigerating system charged with a volatile refrigerant, said secondary system including an evaporator portion arranged to dehydrate air in said warm dry compartment and a condenser portion arranged to transfer a limited amount of heat to said relatively cool compartment.

7. In a refrigerator, a refrigerating system for cooling portions of said refrigerator, a condensing unit forming a part of said system and located adjacent to a rear wall of said refrigerator, a warm dry compartment accessible from the front of said refrigerator, closure means for said compartment arranged to substantially prevent the flow of air into and out of said compartment when the closure means is closed, means exposed to the air of said warm dry compartment adapted to collect moisture from air contained therein, and means for conveying the moisture thus collected into contact with ambient air for the purpose of dissipating said moisture to the air of the room in which the refrigerator is located.

8. In a refrigerator having insulated outer walls, a refrigerating system, a food compartment enclosed by said walls and cooled by said system, a second compartment outside of said insulated walls, means for collecting water condensed within said food compartment, means for collecting water condensed from the air of said second compartment, and means for re-evaporating the water collected by both of the aforesaid means and discharging the water vapor thus formed to ambient air.

9. In a refrigerator, a refrigerated storage space, insulation surrounding said space, a small enclosure within said space arranged to be cooled by heat transfer to the air of said space, a warm dry storage space, and heat transfer means for condensing moisture from the air of said warm dry space by transferring a limited amount of heat from said warm dry space to said small enclosure.

10. In a refrigerator, a warm dry storage space, an opening for access to said space, a movable closure for said opening, a food storage space enclosed by insulated walls, means for cooling the last said space, and means forming a cold surface over which the air within said warm dry space is free to circulate, said means serving to condense moisture from the air of said warm dry storage space, and to transfer latent heat absorbed in condensing water vapor from said warm dry space to said cooled food storage space.

11. In a refrigerator, a refrigerating system, means forming a plurality of spaces cooled by said system, means forming a space heated by said system, means for collecting water condensed from the air of one of said cooled spaces, means for transferring heat from said heated space to one of said cooled spaces and condensing water from the air of said heated space, and means for re-evaporating water condensed from the air of both of said spaces, the last said means serving to mingle the water vapor thus formed with ambient air.

12. In a refrigerator, an insulated compartment, means for cooling said compartment, a warm dry storage compartment exterior to the first said compartment, means for removing moisture from the air of the second said compartment including means having a moisture condensing surface over which the air of the second said compartment is free to circulate, and means for draining the condensed water thus collected away from contact with the air of said warm dry compartment.

13. In a refrigerator, a thermally insulated chamber, a refrigerating system arranged to cool said chamber, to condense moisture therein and to dissipate heat exteriorly thereof, a warm dry compartment for products to be maintained in a dehydrated condition, and means in heat transfer with said system for absorbing water vapor from the atmosphere of the last said compartment and re-evaporating said moisture to ambient air.

14. In a refrigerator, a thermally insulated chamber, a refrigerating system arranged to cool said chamber, to condense water vapor from the air of said chamber and to dissipate heat exteriorly thereof, a warm dry compartment for products to be maintained in a dehydrated condition, means for collecting moisture from the atmosphere of the last said compartment, and means for re-evaporating said moisture to ambient air, said evaporation being accomplished

with the aid of heat obtained from the heat dissipating portion of the refrigerating system.

15. In a refrigerator, a cold food storage space, a refrigerating system for removing heat from said space and dissipating it exteriorly thereof, means enclosing a space for storage or dry products, dehydrating means for said space comprising a moisture absorbing material, means for bringing said material into and out of contact with the air contained within said space for the purpose of dehydrating said air and dissipating the moisture thus collected to ambient air, the last said means being energized gravitationally by changes in the weight of said material due to changes of its moisture content.

16. In a refrigerator, an insulated enclosure, a refrigerating system including means for cooling said enclosure, a non-insulated warm dry compartment outside of said insulated enclosure, an opening for access to said warm dry compartment, a movable closure for said opening, means for cooling a portion of the air and water vapor mixture of said warm dry compartment to condense moisture therefrom by the absorption of latent heat thereof, and means for draining the water of condensation into heat exchange with a warm portion of said system to re-evaporate said water and allow the resulting vapor to mix with ambient atmosphere.

17. In a refrigerator, an insulated enclosure, a refrigerating system including means for cooling said enclosure and condensing water from the atmosphere therein, a warm dry storage compartment outside of the first said enclosure, an access opening for said warm dry compartment, 35 a movable closure for said opening, means forming a cooled surface exposed to air of the warm dry compartment to condense moisture therefrom, means for draining water of condensation from said insulated enclosure, and means for conveying the water of condensation from both sources into heat exchange with a warm portion of said system to re-evaporate said water and discharge the resulting vapor to ambient atmosphere.

18. In a refrigerator, a storage space enclosed within said refrigerator by insulated walls, a refrigerating system including means arranged to cool said space and to condense water from the air and water vapor mixture within said space, an enclosed warm dry storage space outside of said insulated space, an access opening for said warm dry space, a movable closure for said opening, means for utilizing a cooling effect resulting from the operation of said system to condense water vapor from the air and water vapor mixture within said warm dry space, and means for draining said water of condensation from both spaces to a water evaporating device adapted to discharge water vapor to ambient air.

19. In a refrigerator cabinet, a food storage space, a refrigerating system for removing heat from said space and dissipating said heat exteriorly thereof, a warm dry storage space containing air of relatively low humidity, an opening for access to said warm dry space, a movable closure for said opening, means for collecting moisture from said air, and means dissipating it to ambient air.
